COMPRESSOR SHUT-OFF VALVE
MECHANISMWerner F. Boldt, Clayton, Mo., assignor to
Wagner Electric Corporation, St. Louis, Mo.,
a corporation of Delaware

Application July 5, 1938, Serial No. 217,485

12 Claims. (Cl. 303—11)

My invention relates to valve mechanism and more particularly to valve mechanism for shutting off the intake of a compressor to unload it under certain conditions.

One of the objects of my invention is to provide an improved shut-off valve for the intake of a compressor which will be automatically closed when the pressure in the compressor receiver reaches a maximum predetermined value and which will be positively reopened each time air under pressure is used from the receiver by a fluid-actuated system associated therewith.

Another object of my invention is to provide means associated with the shut-off valve mechanism for permitting fluid to be supplied to the compressor intake in the event the pressure of the fluid in the receiver should drop below a predetermined minimum value during the time fluid is not being used from the receiver by the fluid pressure-actuated system.

Other objects of my invention will become apparent from the following description taken in connection with the accompanying drawings in which Figure 1 is a view of a compressor, a receiver therefor, and a fluid-actuated system showing my improved compressor intake shut-off valve mechanism associated therewith; Figure 2 is a longitudinal cross-sectional view of the valve mechanism taken on the line 2—2 of Figure 1; and Figures 3 and 4 are cross-sectional views taken on the lines 3—3 and 4—4, respectively, of Figure 2.

Referring to the drawings in detail, the compressor 1, with which I have illustrated my shut-off valve mechanism as being associated, is of the rotary type having a stator 2 and an eccentrically mounted rotor 3 provided with a plurality of blades 4 (one only being shown). The stator has an intake port 5 and an outlet port 6, the latter opening into an oil dome 7 which is connected to a pressure tank 8 by means of a conduit 9, the oil dome and pressure tank both being considered as the receiver of the compressor. The outlet of the compressor has associated therewith a check valve 10 for preventing back flow of the compressed fluid and associated with the outlet of the dome is another check valve 11. The pressure tank 8 is shown as connected by a conduit 12 with a fluid motor 13 which may be employed to operate any mechanism desired, as for example, a braking mechanism. The fluid pressure employed to actuate the fluid motor is controlled by a valve 14 in conduit 12, this valve being shown as a hand valve but it is understood that other valve mechanisms

such as a foot control valve may be employed if desired.

In compressors of the type described which are of well-known construction it is desirable to automatically prevent the compressor from compressing fluid after the fluid in the receiver has been placed under a predetermined maximum pressure. This is best accomplished by shutting off the intake port so the air or other fluid which is being compressed by the compressor is not permitted to enter the compressing chamber. It is also desirable that the intake port not only be automatically closed at the proper time but that it also be reopened whenever the pressure in the receiver drops.

The valve mechanism comprises a casing 16 which is provided with parallel bores 17 and 18, the bore 18 being formed with two chambers 19 and 20 connected by a passage 21 and bore 17 being formed with two chambers 22 and 23 connected by a passage 24. The casing is also provided with an inlet 25 which connects with chambers 19 and 22 and with an outlet passage 26 which communicates with chambers 20 and 23. The inlet has associated therewith an air cleaner 27 and the outlet is adapted to communicate with the intake port 5 of the compressor when the valve mechanism is mounted on the compressor. The chamber 19 has loosely mounted therein a slide valve member 28 which is adapted to cooperate with a seat 29 for closing passage 21 between chambers 19 and 20. The chamber 19 at the rear of the valve member 28 is connected to the dome of the compressor by a conduit 30. Communication between the conduit and the chamber at the rear of the piston is controlled by a valve 31 biased against its seat by spring 32 interposed between the valve element and the member 33 supported by a hollow plug of the casing.

Within the chamber 20 is a piston 34 which carries a rod 35 extending through passage 21 to a point spaced from valve member 28 when this valve member is in the position shown. A spring 36 surrounds the rod and is interposed between the valve member 28 and the piston 34 and normally tends to hold the valve member 28 unseated. There is also provided a spring 37 for maintaining piston 34 at the right end of chamber 20. The right end of the chamber 20 is connected by a conduit 38 with conduit 12 at a point between the control valve 14 and fluid motor 13.

Within chamber 23 is a slide valve member 39 which is adapted to cooperate with a seat 40 to

- close the passage 24 between chambers 22 and 23. The valve member is biased to open position by spring 41 interposed between the valve member and a cap 42 closing the end of chamber 22. 6 The right end of chamber 23 is connected by a conduit 43 to conduit 9 leading from the oil dome to the tank.

The springs of the valve mechanism may be designed to cause the valve mechanism to operate 10 to maintain any predetermined maximum pressure in the receiver which is desired. In the valve mechanism shown, the spring 32 is so designed that fluid under pressure will not be admitted into the chamber at the rear of the valve member 28 until the fluid pressure in the dome reaches one hundred pounds per square inch. The spring 41 is so designed that it will unseat the valve member 39 when the air pressure acting on it from the receiver is ninety pounds per 20 square inch. The spring 36 is a light spring, only being strong enough to keep valve member 28 unseated if there is no pressure acting on this member tending to move it to closed position. The spring 37 is also a relatively light spring being 25 only strong enough to normally bias piston 34 to the right end of chamber 20 when no pressure is acting on the forward portion of the piston.

In operation, when the parts of the valve mechanism are in the position shown, air will 30 be free to be drawn into the intake port of the compressor and be compressed thereby and forced out into the oil dome and into the tank. When the pressure in the tank exceeds ninety pounds per square inch, there will be sufficient 35 pressure acting on valve member 39 to move it to the left and close passage 24. This will not prevent the compressor from continuing to operate under load since passage 26 leading to the intake is still in communication with passage 40 25 by means of passage 21. When the pressure in the oil dome and the tank reaches one hundred pounds per square inch, valve element 31 will be unseated and pressure from the dome will enter the chamber at the rear of the valve member 28. When sufficient pressure is present 45 in this chamber to overcome the biasing action of the weak spring 36 (this pressure need not be greater than a few pounds per square inch), the valve member will be moved against seat 50 29, thereby preventing air from being drawn into the compressor. The compressor will now be unloaded and will run idle.

It is to be noted that the valve member 28 is so associated with its seat and the passage 55 26 leading to the intake of the compressor that the vacuum of the compressor will assist in holding the valve member 28 seated once it is moved to its seat by sufficient pressure acting thereon. This arrangement insures that the intake to the 60 compressor will be positively closed against leakage.

If, after the fluid in the dome and tank has been brought up to its maximum pressure and the compressor has been unloaded, fluid should 65 be used to operate the fluid motor 13 by operation of the control valve 14, there will be a drop in the pressure in the tank and dome. This, however, will be immediately replaced by the compressor since the pressure admitted to the 70 fluid motor is also effective through conduit 38 to move piston 34 to the left and against spring 37 and cause rod 35 to engage valve member 28 and disengage it from seat 29. The intake of the compressor is again connected to the atmosphere. 75 After the compressor has again restored

the pressure in the dome and tank to its maximum, the valve mechanism will operate in a manner already described to prevent air from being drawn into the compressor intake.

There may be conditions where fluid motor 13 may not be operated over a long period of time and because of a small leak in the compressor dome or tank or the connecting conduits, the receiver pressure may drop. In order to insure that the pressure in the tank and dome 10 under these conditions will be maintained at a reasonable minimum value, valve member 39 and associated structure, already described, has been incorporated into the mechanism. As soon as the pressure in the tank reaches the minimum 15 value of say eighty pounds per square inch, spring 41 will function to move valve member 39 to the right, thereby opening passage 24. The passage 26 is now in communication with passage 25 leading to the atmosphere and the compressor 20 may now begin to operate. As soon as the compressor begins to operate, the vacuum effective on the valve member 28 tending to hold it seated will be broken and the valve member will be moved to the left under the action of spring 36 25 and air may pass through the passage 21. When the tank pressure reaches sufficient value, valve member 39 will be reseated but the compressor will continue to operate until the pressure in the dome and tank again reaches the maximum 30 of one hundred pounds per square inch when the valve member 28 will be closed thereby unloading the compressor.

From the foregoing description it is apparent 35 that I have constructed an efficient and reliable valve mechanism. The valve member 28 is operable by very small pressures because no packing cups are employed to cause increased frictional resistance. The mechanism insures that the receiver pressure will be maintained above a minimum 40 value under all circumstances.

Being aware of the possibility of modifications in the particular structure herein described without departing from the fundamental principles of my invention, I do not intend that its scope 45 be limited except as set forth by the appended claims.

Having fully described my invention, what I claim as new and desire to secure by Letters Patent of the United States is:

1. In apparatus of the class described, a fluid compressor provided with an intake port and an exhaust port, a fluid pressure receiver connected to the exhaust port, a fluid pressure-actuated system adapted to be operated by fluid pressure 55 from the receiver, valve means comprising a movable valve member for controlling the intake, means for automatically moving said valve member to closed position when the pressure in the receiver is a predetermined value, a movable member for engaging the valve member to move it to a position to open the intake, a spring for normally biasing the member to an inoperative position independently of the valve, a fluid motor for actuating said movable member, and 60 means for operating said fluid motor by pressure from the fluid pressure-actuated system when the latter is operated.

2. In apparatus of the class described, a fluid compressor provided with an intake port and 70 an exhaust port, a fluid pressure receiver connected to the exhaust port, a fluid pressure-actuated system adapted to be operated by fluid pressure from the receiver, valve means comprising a movable valve member for controlling 75

the intake and when in closed position being so maintained by the suction of the compressor, means for automatically moving said valve member to closed position when the pressure in the receiver is a predetermined value, a fluid motor comprising a movable element in alignment with the movable valve member, a member carried by the movable element for engaging the valve member and causing it to be unseated when the fluid motor is operated, and means for operating the fluid motor by fluid pressure from the fluid pressure-actuated system when the latter is operated.

3. In apparatus of the class described, a fluid compressor provided with an intake port and an exhaust port, a fluid pressure receiver connected to the exhaust port, a casing provided with a passage leading to the intake, means comprising a movable valve member for closing the passage when the pressure in the receiver is a predetermined value, said valve member being so associated with the intake that suction of the compressor will assist in holding the valve member seated, means forming a second passage to the intake, a valve for said second passage, means for maintaining said last named valve closed by the pressure from the receiver, and means for causing said last named valve to assume open position when the pressure in the receiver drops below the pressure necessary to maintain said valve closed.

4. In apparatus of the class described, a fluid compressor provided with an intake port and an exhaust port, a fluid pressure receiver connected to the exhaust port, valve means comprising a movable valve member for controlling the intake, means for automatically moving said valve member to closed position when the pressure in the receiver is a predetermined value, said valve member being so associated with the intake that suction of the compressor will assist in holding the valve member seated, a by-pass around said valve means, a valve for said by-pass, and means for causing said last named valve to be opened when the pressure in the receiver drops to a point below the predetermined value.

5. In apparatus of the class described, a fluid compressor provided with an intake port and an exhaust port, a fluid pressure receiver connected to the exhaust port, a casing provided with a passage leading to the intake, means comprising a movable valve member for closing the passage when the pressure in the receiver is a predetermined value, said valve member being so associated with the intake that suction of the compressor will assist in holding the valve member seated, means forming a second passage to the intake, valve means including a movable element for controlling the second passage, a spring for biasing the valve element to closed position, and means for moving said valve element to closed position by pressure from the receiver, said valve element being opened by the spring when the pressure in the receiver drops to a value below the predetermined pressure.

6. In apparatus of the class described, a fluid compressor provided with an intake port and an exhaust port, a fluid pressure receiver connected to the exhaust port, a casing provided with a passage leading to the intake and having associated therewith a valve seat, means comprising a movable valve member for cooperating with said seat, a spring for biasing the valve member off its seat, means for automatically seating said valve member when the pressure in the receiver

is a predetermined value, said valve member and seat being so associated with the intake that suction of the compressor will assist in holding the valve member seated, and means independent of the valve member and operable by a drop in pressure in the receiver below the predetermined value for connecting the intake to the source of fluid for the compressor, said valve member being permitted to open under the action of its spring when the suction of the compressor is not effective thereon.

7. In apparatus of the class described, a fluid compressor provided with an intake port and an exhaust port, a fluid pressure receiver connected to the exhaust port, a fluid pressure-actuated system adapted to be operated by fluid pressure from the receiver, valve means comprising a movable valve member for controlling the intake, means for automatically moving said valve member to closed position when the pressure in the receiver is a predetermined value, said valve member being so associated with the intake that suction of the compressor will assist in holding the valve member seated, means for causing said valve member to be unseated by fluid pressure from the fluid pressure-actuated system when it is operated, and means independent of the valve means for permitting fluid to enter the intake of the compressor when the fluid pressure in the receiver drops below the predetermined pressure.

8. In apparatus of the class described, a fluid compressor provided with an intake port and an exhaust port, a fluid pressure receiver connected to the exhaust port, a fluid pressure-actuated system adapted to be operated by fluid pressure from the receiver, valve means comprising a movable valve member for controlling the intake, means for automatically moving said valve member to closed position when the pressure in the receiver is a predetermined value, said valve member being so associated with the intake that suction of the compressor will assist in holding the valve member seated, means for causing said valve member to be unseated by fluid pressure from the fluid pressure-actuated system when it is operated, and means independent of the valve means for permitting fluid to enter the intake of the compressor when the fluid pressure in the receiver drops below the predetermined pressure, said last named means comprising a valve-controlled passage having a valve element acted on by fluid pressure from the receiver and a spring for biasing the valve element toward open position.

9. In apparatus of the class described, a fluid compressor provided with an intake port and an exhaust port, a fluid pressure receiver connected to the exhaust port, a fluid pressure-actuated system adapted to be operated by fluid pressure from the receiver, a casing provided with a passage leading to the intake, means comprising a movable valve member for closing the passage when the pressure in the receiver is a predetermined value, said valve member being so associated with the intake that suction of the compressor will assist in holding the valve member seated, means forming a second passage to the intake, a valve for said second passage, means for maintaining said last named valve closed by the predetermined pressure in the receiver, means for causing said last named valve to assume open position when the pressure in the receiver drops below the predetermined value, and means operable by fluid pressure when the fluid pressure-

actuated system is operated to cause the movable valve member to be opened.

10. In apparatus of the class described, a fluid compressor provided with an intake port and an exhaust port, a fluid pressure receiver connected to the exhaust port, a casing provided with a passage leading to the intake, a movable valve member in said casing and adapted to be moved to close the passage by a low pressure, means 5 for subjecting said valve member to a fluid pressure from the receiver only when the pressure of the fluid in the receiver is above a predetermined value, said predetermined pressure being above that necessary to move the valve member, 10 means forming a second passage to the intake, a valve for said second passage, means for maintaining said second named valve closed when the pressure in the receiver is above a predetermined value but below the first named predetermined value, and means for causing said last named 15 value, and means for causing said last named valve to assume open position when the pressure in the receiver drops below the pressure necessary to maintain said valve closed.
11. In apparatus of the class described, a fluid compressor provided with an intake port and an exhaust port, a fluid pressure receiver connected to the exhaust port, a casing provided with a passage leading to the intake, a movable valve member in said casing for closing the passage, 20 a light spring for biasing the valve member open 25

but permitting the valve to be closed by a low pressure, means comprising a pressure valve for permitting said valve member to be subject to a fluid pressure from the receiver only when the pressure of the fluid in the receiver is above a 5 predetermined value, means forming a second passage to the intake, a valve for said second passage, means for maintaining said second named valve closed when the pressure in the receiver is above a predetermined value but below 10, the first named predetermined value, and means for causing said last named valve to assume open position when the pressure in the receiver drops below the pressure necessary to maintain said valve closed.

12. In apparatus of the class described, a fluid compressor provided with an intake port and an exhaust port, a fluid pressure receiver connected to the exhaust port, a casing provided with a passage leading to the intake, a movable valve member in said casing for closing the passage, a light spring for biasing the valve member open but permitting the valve to be closed by a low pressure, and means comprising a pressure valve for permitting said valve member to be subject 20 to a fluid pressure from the receiver only when the pressure of the fluid in the receiver is above a predetermined value.

WERNER F. BOLDT. 30
